UNITED STATES PATENT OFFICE.

FRANK DESORT, OF CLEVELAND, OHIO, ASSIGNOR OF ONE-HALF TO GEORGE EIERMANN, OF CLEVELAND, OHIO.

INTERNAL-COMBUSTION ENGINE.

1,147,313.

Specification of Letters Patent.

Patented July 20, 1915.

Application filed November 9, 1914. Serial No. 871,013.

To all whom it may concern:

Be it known that I, FRANK DESORT, citizen of the United States, residing at Cleveland, in the county of Cuyahoga and State 5 of Ohio, have invented certain new and useful Improvements in Internal-Combustion Engines, of which the following is a specification.

This invention relates to internal combustion engines, and has for its object to provide an improved engine of a type employing a plurality of cylinders, the cylinders being arranged in parallel relation around a common center at which the driven shaft 10 is located, the axis of the shaft being parallel to that of each cylinder. The power is transmitted to the main shaft by means of radial crank shafts to which the pistons are connected, and each crank shaft has a pinion 15 in mesh with a large gear on the main shaft, the large gear serving also as a fly wheel. The crank shafts and gearing are all inclosed in a single crank casing, which may 20 also form an oil chamber, the whole construction providing a very compact and effective arrangement for a multicylinder engine.

The cylinders are all mounted in position on the crank case, at one end thereof, so 30 that they are conveniently accessible, and the inlet and exhaust connections, as well as the connections for the cooling system, are easily made. Each cylinder is provided with suitable valves which are operated by 35 a rocker, and each rocker is operated by a rod which works through the end of the crank case and is moved by means of a cam plate mounted on the main shaft within said case, the valves being thus readily accessible 40 without removing the cylinders or any part of the crank case, the symmetrical arrangement giving an advantageous uniformity to the valve operations.

The engine is illustrated in the accompanying drawings in which:

Figure 1 is an end view thereof. Fig. 2 is a side view partly in section. Figs. 3, 4 and 5 are details in section, showing the valves in different positions.

60 The operation is according to the four cycle type.

In the drawings, 7 indicates one end or part of the crank case and 8 the other part, the cylinders 9 being mounted on the latter

in parallelism around a common center at 55 which is located the main shaft 19 which extends through the opposite end of the crank case, having a bearing at 20 in the end 8 and another bearing at 21, in the opposite end. Each cylinder has a water 60 jacket 10, and a guide 9^a for the valve rod 16. These rods are preferably located on the inner side of each cylinder and each rod is connected at its outer end, at 14^c, to a rocker 14 which turns on a pivot 15^a on a 65 post 15 at the top of the cylinder. The inlet valve 12 and the exhaust valve 13 are located in the cylinder head, and the stems 12^a and 13^a thereof extend through the head to contact with the opposite ends of the 70 rocker 14, at surfaces 14^a and 14^b, respectively, the stems being provided with springs 12^b and 13^b tending to close the valves. The inlet connections are indicated at 30 and the exhaust connections at 31, the 75 latter extending to an exhaust manifold 32 communicating with an outlet pipe 33, the manifold being in the form of a ring. The inlet manifold, not shown, may have a similar form.

The cylinders are located over corresponding openings in the crank case end, and each cylinder has a piston 22 connected by a rod 23 to a crank 24 which is mounted in hangers 25 and 26 on the inside of the crank case, 80 and the outer end of each crank has a stub shaft 24^a carrying a pinion 27 which meshes with a large ring gear 28 mounted at 19^a on arms 19^b projecting from the main shaft 19. Said shaft also carries a cam plate 18 which 85 has neutral surfaces 18^b permitting both valves to be closed, raisers 18^a to open the exhaust valves, and drops 18^c to permit the inlet valves to open. In the arrangement shown, having seven cylinders, there will be 90 four rises and drops arranged symmetrically around the cam. Each valve rod has a spring 17 which holds the roller 17^a, at the inner end of the rod, against the cam plate and which operates the rod to open the inlet valve. The rod is squared as at 16^a where it passes through the opening 8^a in the end plate 8 of the crank case.

In operation, the explosion of the motive fluid in the cylinders turns the crank shafts 105 which through the several pinions and the main gear drives the main shaft, and the cam plate 18 carried thereby operates the

valves in proper succession to control the inlet to and exhaust from the several cylinders.

The invention is not limited to the particular number of cylinders, nor to the other features shown and described, except as indicated in the following claims; therefore changes may be made within the scope of the invention.

10. What I claim as new is:—

1. The combination of a crank case, a main shaft extending therein, a plurality of cylinders mounted in parallelism on one end of the crank case and around a common center at the axis of the shaft, inlet and exhaust valves on each cylinder, operating devices for the valves of each cylinder including a rod extending through the end of the crank case, and means within the crank case, actuated by the main shaft, for operating said rods.
2. The combination of a crank case, a main shaft therein, a cylinder on the end of the crank case, parallel to the axis of the main shaft, a rocker on the outer end of the cylinder, inlet and exhaust valves on the

cylinder, operatively connected to said rocker, a reciprocating rod working through the end of the crank case, parallel to said cylinder and connected at its outer end to 30 said rocker, and a cam plate on the main shaft, bearing against the inner end of said rod.

3. The combination of a crank case, a main shaft extending therein, a plurality of 35 parallel cylinders arranged in a ring on one end of the case, around the axis of the main shaft as a center, said cylinders being provided with inlet and exhaust valves, a plurality of rods corresponding to the cylinders and operatively connected to the valves thereof respectively, said rods working parallel to the main shaft through the said end of the crank case, and means on the main shaft to operate said rods.

In testimony whereof, I affix my signature in presence of two witnesses.

FRANK DESORT.
